CLAIM

The ornamental design for a multiple electrical outlet adapter, as shown and described.

DESCRIPTION

FIG. 1 is a front elevational view of a multiple electrical outlet adapter showing my new design;

FIG. 2 is a left side elevational view thereof, the right side elevational view being a mirror image. The broken lines are included only for the purpose of illustrating the position of the receptacle per se and form no part of the claimed design;

FIG. 3 is a top plan view thereof;

FIG. 4 is a bottom plan view thereof;

FIG. 5 is a back elevational view thereof;

FIG. 6 is a left side elevational view of a multiple electrical outlet adapter showing a second embodiment of my new design, the right side elevational view being a mirror image, with the front and rear elevational views, and the top and bottom plan views being the same as the first embodiment;

FIG. 7 is a left side elevational view of a multiple electrical outlet adapter showing a third embodiment of my new design, the right side elevational view being a mirror image, with the front and rear elevational views, and the top and bottom plan views being the same as the first embodiment;

FIG. 8 is a left side elevational view of a multiple electrical outlet adapter showing a fourth embodiment of my new design, the right side elevational view being a mirror image, with the front and rear elevational views, and the top and bottom plan views being the same as the first embodiment;

FIG. 9 is a left side elevational view of a multiple electrical outlet adapter showing a fifth embodiment of my new design, the right side elevational view being a mirror image, with the front and rear elevational views, and the top and bottom plan views being the same as the first embodiment;

FIG. 10 is a left side elevational view of a multiple electrical outlet adapter showing a sixth embodiment of my new design, the right side elevational view being a mirror image, with the front elevational view being the same as the first embodiment. The broken lines are included only for the purpose of illustrating the position

of the receptacle per se and form no part of the claimed design;

FIG. 11 is a back elevational view thereof;

FIG. 12 is a top plan view thereof, the bottom plan view being a mirror image;

FIG. 13 is a left side elevational view of a multiple electrical outlet adapter showing a seventh embodiment of my new design, the right side elevational view being a mirror image, with the front and rear elevational views, and the top and bottom plan views being the same as the sixth embodiment;

FIG. 14 is a left side elevational view of a multiple electrical outlet adapter showing an eighth embodiment of my new design, the right side elevational view being a mirror image, with the front and rear elevational views, and the top and bottom plan views being the same as the sixth embodiment;

FIG. 15 is a left side elevational view of a multiple

electrical outlet adapter showing a ninth embodiment of my new design, the right side elevational view being a mirror image, with the front and rear elevational views, and the top and bottom plan views being the same as the sixth embodiment;

FIG. 16 is a left side elevational view of a multiple electrical outlet adapter showing a tenth embodiment of my new design, the right side elevational view being a mirror image, with the front and rear elevational views, and the top and bottom plan views being the same as the sixth embodiment;

FIG. 17 is a front, bottom and right side perspective view of the first embodiment. The broken lines are included only for the purpose of illustrating the position of the receptacle per se and form no part of the claimed design.
